UNITED STATES PATENT OFFICE

136,273

DESIGN FOR A COMBINED NEUROLOGICAL HAMMER, BRUSH, AND NEEDLE

Julius Brandenburg, New York, N. Y.

Application June 9, 1943, Serial No. 110,419

Term of patent 7 years

To all whom it may concern:

Be it known that I, Julius Brandenburg, a citizen of Hungary and a resident of the city of New York, in the county of New York and State of New York, have invented a new, original, and ornamental Design for a combined Neurological Hammer, Brush, and Needle, of which the following is a specification, reference being had to the accompanying drawing, forming a part thereof.

Fig. 1 is a plan view of my combined neurological hammer, brush, and needle showing my new design.

Fig. 2 is a plan view of the steel point unscrewed from the top of the hammer.

Fig. 3 is a plan view of the brush unscrewed from the hollow handle.

I claim:

The ornamental design for a combined neurological hammer, brush, and needle, substantially as shown.

JULIUS BRANDENBURG.
